UNITED STATES PATENT OFFICE.

THOMAS J. AKERS AND HUBERT E. SMITH, OF LATAH, WASHINGTON.

FENCE-POST.

No. 926,229.

Specification of Letters Patent. Patented June 29, 1909.

Application filed January 19, 1909. Serial No. 473,163.

To all whom it may concern:

Be it known that we, THOMAS J. AKERS and HUBERT E. SMITH, citizens of the United States, residing at Latah, in the county of 5 Spokane, State of Washington, have invented certain new and useful Improvements in Fence-Posts; and we do hereby declare the following to be a full, clear, and exact description of the invention, such as 10 will enable others skilled in the art to which it appertains to make and use the same.

This invention relates to improvements in fence posts, and has for one of its objects to improve the construction and increase the 15 efficiency and utility of devices of this character.

Another object of the invention is to provide a tubular metal fence post of improved construction and increased strength without 20 material increase in expense or weight, and to provide means whereby the strand wires of the fence are supported by the structure of the post.

With these and other objects in view the 25 invention consists generally in a tubular post having its walls formed into a plurality of circumferential corrugations, and with strand wire fastening devices located in the valleys or hollows between the corrugations, 30 whereby the projecting portions of the corrugations are utilized to assist in supporting the strand wires.

The invention further consists in certain novel features of construction as hereafter 35 shown and described and then specifically pointed out in the claim, and in the drawings illustrative of the preferred embodiment of the invention.

Figure 1 is a side elevation of a portion 40 of a fence, including one of the corners with the improved posts and fastening devices employed therein. Fig. 2 is an enlarged, side view of a portion of one of the posts, illustrating the construction more fully.

45 The improved post is constructed from a section of tubing, preferably tapering from end to end and formed into a plurality of circumferential corrugations whereby alternating annular ribs and hollows are formed. 50 The post will be preferably constructed from sheet metal of any required quality or "gage", and will preferably be galvanized or otherwise coated or treated to prevent corrosion.

55 The posts are represented respectively at

10 and tapered from end to end with the larger end inserted into the ground represented at 11, and each post formed by suitable machinery into a plurality of circumferential corrugations whereby spaced annular ribs 12 and hollows or valleys 13 are produced, as shown. 60

Formed at suitable intervals through the side walls of the post are inverted V-shaped clefts 14, the clefts formed in the valleys 13 and by means of which V-shaped tongues 15 are produced which are adapted to be bent outwardly to form supports for the strand wires represented at 16, and then the points bent inwardly over the strand wires to lock them in position. Each strand wire is thus firmly locked in one of the valleys 13, and as the ribs 12 above and below the strand wires overhang the same, they materially assist in holding the strand wires in position. 70

Formed in each of the clefts 14 near its "root" portion is a recess 17 which forms a convenient means for inserting an implement, such as a pointed nail or rod to pry the tongue 15 out of its seat in the cleft when it is desired to detach the strand wires. The recess thus forms an important feature of the invention and materially increases the utility and efficiency of the device, as the labor required to detach the tongue when the strand wire is to be removed is very materially lessened, as will be obvious. 75

In Fig. 1 is shown the means for securing the posts at the corners consisting in coupling the corner post and the next line post by diagonally arranged wire braces 18 looped at the ends around the posts and located between the corner post and the next line post a brace member 19, the latter preferably of wood with notches in the ends to engage in the uppermost valleys or hollows 13 of the posts. By this simple means the corner post is stayed and supported and rendered capable of withstanding the severe strains to which posts located at the corners of fences are subjected. The posts may be of any required size, but in practice ordinary posts will be about 6 $\frac{1}{2}$ feet long, 2 $\frac{1}{2}$ inches in the smaller ends, and 4 $\frac{1}{2}$ inches in diameter at the larger ends, but it will be understood that these dimensions may vary as required. 95

The improved device is simple in construction, can be inexpensively manufactured, and being of metal and galvanized will be practically indestructible. 105

What is claimed is:

A tubular fence post having a plurality of V-shaped clefts forming tongues adapted to be bent inwardly over a wire to secure the same to the post, each of said clefts having a lateral recess which communicates with the adjacent opening formed by the cleft, to facilitate the release of the tongue.

In testimony whereof, we affix our signatures in presence of two witnesses.

THOMAS J. AKERS.
HUBERT E. SMITH.
